MECHANISM FOR DISCONNECTING AND RE-
INSERTING THE LIFTING MOVEMENT OF
THE CLOTH FEED CLAW IN SEWING MA-
CHINESGiuseppe Amman, Milan, Italy, assignor to Fra-
telli Borletti Societa per Azioni, Milan, Italy,
a body corporateApplication March 28, 1951, Serial No. 217,932
In Italy April 7, 1950

2 Claims. (Cl. 112—210)

1

The present invention relates to a mechanism applicable to sewing machines for determining the disconnecting of the lifting movement of the cloth feed dog, when for certain uses of the machine, as for instance lace or mending works, said lifting is to be eliminated; and the re-inserting of said movement when, as for instance in the case of ordinary sewing, it becomes necessary for the feeding of the cloth.

Said mechanism is characterized by the forked lever that generates under the action of an eccentric engaged in the fork the lifting of the dog by means of a pin therewith connected and penetrating into a slot of said dog, being mounted on an axially slideable bar, which may be displaced forward or backwards by means of a lever that can be operated by the operator, in such a way that, when the bar is pulled in one direction, the pin connected to the forked lever, following the latter, comes out of the opening in the dog, and penetrates again into said opening when the bar is pushed in the opposite direction.

Said mechanism is simple and practical, and is particularly adapted to be used in connection with machines in which the eccentric operating the forked lever is arranged with its relative shaft underneath the base plate.

Further particulars and advantages of the object of the invention will appear from an embodiment thereof illustrated in the annexed drawing, in which:

Fig. 1 shows in perspective view the assembly of the mechanism as applied to a sewing machine;

Fig. 2 is a perspective view of a part of the mechanism, separated into its elements in order that its construction and working will be better understood.

Bar 1 is slidably mounted within supports 2 and 3 integral with the base of the machine. An appendage 5, fastened rigidly to said bar, is held in a fork 6 forming an extremity of lever 7 pivoted at 8.

At the other end of bar 1 is loosely mounted lever 9 having a pin shaped appendage 10.

On the hub of lever 9 is mounted hub 11 of fork 12. Said hub is connected to the hub of lever 9 by means of a screw 13, or any other equivalent member, in such a way that the position of shaft 10 relative to fork 12 may be adjusted at will, in order to give dog 14 the right height.

Levers 9 and 10 and consequently fork 11—12 are prevented from sliding along bar 1 by suitable stop washers 15, which, while preventing axial displacements relative to bar 1, do not prevent

rotations in respect to said bar of said lever 9—10 and consequently of fork 11—12.

Bar 1 is prevented from turning by fork 6, or by any other suitable member, a key or a screw; for instance, entering a longitudinal groove or keyway of said bar.

Pin 10 enters into an opening 17 cut in the support of the dog.

Fork 12 embraces a rotating or oscillating eccentric 18, from which it is given the reciprocating up and down movement.

From the foregoing the operation of the mechanism is easily understandable.

Eccentric 18 during its rotation transmits a motion to fork 12 which transmits it to pin 10 that, in its turn, transmits it to dog 14; this occurs when lever 7 is fully displaced to the right. When, on the contrary, lever 7 is fully displaced to the left, bar 1 slides toward the right as per arrow 19 and fork 12 slides on eccentric 18, sufficiently long as not to lose contact with the same.

In this displacement pin 10 comes out of opening 17, thus leaving the support of the dog, which thus remains in a low position and is no more effected by the up and down movements of fork 12 and pin 10. In the inverted movement of lever 7 the extremity of pin 10, which is conical at its tip, re-enters opening 17, and communicates again said movements to dog 14.

It is understood that the constructive particulars of the mechanism may be made different from those represented in the drawings and above described, the mechanism itself still remaining at all times within the range of the invention.

What I claim is:

1. A mechanism for lifting the feed dog of a feeder in a sewing machine comprising a shaft, means mounting the shaft for axial slideable movement, a lever freely rockably mounted on the shaft, means for securing the lever on the shaft against axial movement relative to the shaft, said lever having a bifurcated end, an elongated cam rotatably mounted with its axis parallel to the shaft and embraced by the bifurcations of said lever for imparting rocking movement to said lever, a pin carried by said lever and spaced from said shaft and engageable with said feed dog to impart up and down movement to the dog, and means for axially shifting the shaft to displace the lever axially along its cam and to shift the pin into and out of driving engagement with the dog.

2. A mechanism for lifting the feed dog of a feeder in a sewing machine comprising a shaft,

means mounting the shaft for axially slidable movement, a crank lever having a hub freely rockably mounted on the shaft, means for securing the lever hub on the shaft against axial movement relative to the shaft, a cam follower lever mounted on the hub of the crank lever, means for adjustably fixing the cam follower lever on the hub of the crank lever, said cam follower lever having a bifurcated end, an elongated cam rotatably mounted with its axis parallel to the shaft and embraced by the bifurcations of said lever for imparting rocking movement to said levers about said shaft, a pin carried by the crank lever and spaced from the shaft and engageable with said feed dog to impart up and down movement to the dog, and means for axially

shifting the shaft to displace the cam follower lever axially along the cam and to shift the pin carried by the crank lever into and out of engagement with the dog.

GIUSEPPE AMMAN.
